CLAIM

The ornamental design for a case for portable electronic device as shown and described.

DESCRIPTION

FIG. 1 is a front perspective view of case for portable electronic device showing my new design.

FIG. 2 is a top plan view thereof.

FIG. 3 is a bottom plan view thereof.

FIG. 4 is a front elevational view thereof showing the case for portable electronic device on an enlarged scale for clarity of disclosure.

FIG. 5 is a rear elevational view thereof showing the case for portable electronic device on an enlarged scale for clarity of disclosure.

FIG. 6 is a left elevational view thereof.

FIG. 7 is a right elevational view thereof; and,

FIG. 8 is a rear perspective view thereof.

The broken lines in the drawing figures depict portions of the case for portable electronic device that form no part of the claimed design.
